POWDER BOX OR THE LIKE

Joseph C. Foster, Leominster, Mass., assignor to Foster Grant Co., Inc., Leominster, Mass., a corporation of Massachusetts

Application December 21, 1949, Serial No. 6,755

Term of patent 14 years

(Cl. D86—10)

To all whom it may concern:

Be it known that I, Joseph C. Foster, a citizen of the United States, residing at Leominster, Worcester County, State of Massachusetts, have invented a new, original, and ornamental Design for a Powder Box or the like, of which the following is a specification, reference being had to the accompanying drawing, forming part thereof, in which:

Fig. 1 is a top plan view of a powder box or the like showing my new design; and

Fig. 2 is a side view of the cover removed from the box, the box being shown in dot and dash lines.

The characteristic features of the design are shown in full lines.

I claim:

The ornamental design for a powder box or the like, substantially as shown and described.

JOSEPH C. FOSTER.
